US00D809775S

(12) **United States Design Patent** (10) **Patent No.:** **US D809,775 S**
Ma (45) **Date of Patent:** **** Feb. 13, 2018**

(54) **UMBRELLA RUNNER**

(71) Applicant: **Zhun-An Ma**, Arcadia, CA (US)

(72) Inventor: **Zhun-An Ma**, Arcadia, CA (US)

(**) Term: **15 Years**

(21) Appl. No.: **29/581,440**

(22) Filed: **Oct. 19, 2016**

(51) **LOC (11) Cl. 03-03**

(52) **U.S. Cl.**

USPC **D3/10**

(58) **Field of Classification Search**

USPC D3/10; D8/356, 396, 72, 395, 10, 103,
D8/105, 106, 119, 308, 309, 310;

(57) **CLAIM**

The ornamental designs for an umbrella runner, as shown and described.

DESCRIPTION

FIG. 1 is a top perspective view of one embodiment of an umbrella runner;

FIG. 2 is a bottom perspective view of the embodiment of FIG. 1;

FIG. 3 is a front view of the embodiment of FIG. 1;

FIG. 4 is a rear view of the embodiment of FIG. 1;

FIG. 5 is a right side view of the embodiment of FIG. 1;

FIG. 6 is a left side view of the embodiment of FIG. 1;

FIG. 7 is a top view of the embodiment of FIG. 1; and,

FIG. 8 is a bottom view of the embodiment of FIG. 1.

The broken lines represent portions of the umbrella runner that form no part of the claimed design.

1 Claim, 7 Drawing Sheets
